DESIGN FOR A TWINE HOLDER

Herbert H. Rominger, Oakland, Calif., assignor to
J. Edney Harton, Oakland, Calif.

Application June 10, 1938, Serial No. 77,732

Term of patent 14 years

To all whom it may concern:

Be it known that I, Herbert H. Rominger, a citizen of the United States and residing at Oakland, county of Alameda, and State of California, have invented a new, original, and ornamental Design for a Twine Holder, of which the following is a specification, reference being had to the accompanying drawing, forming a part thereof.

Fig. 1 is a top plan view of a holder showing my design.

Fig. 2 is a side elevational view of the holder of Fig. 1, showing my design as viewed from the side.

I claim:

The ornamental design for a twine holder, as shown.

HERBERT H. ROMINGER.
